Patented Mar. 13, 1917.

UNITED STATES PATENT OFFICE.

FRED BLATTNER, JR., OF BROOKLYN, NEW YORK.

OPERATING MECHANISM FOR TUBBING-MACHINES.

1,219,231.

Specification of Letters Patent. Patented Mar. 13, 1917.

Application filed August 23, 1916. Serial No. 116,477.

To all whom it may concern:

Be it known that I, FRED BLATTNER, Jr., a citizen of the United States, residing at Brooklyn, in the county of Kings and State 5 of New York, having invented certain new and useful Improvements in Operating Mechanism for Tubbing-Machines, and do hereby declare that the following is a full, clear, and exact description of the same, reference being had to the annexed drawings, making a part of this specification, and to the letters and figures of reference marked thereon.

My invention relates to the swinging legs 15 of tubing machines which are machines for leathering furriers' skins such as rats, skunks, etc., that are used in the manufacture of coats, muffs and neck-pieces. These legs as ordinarily constructed are of wood. 20 The object of my invention is to provide a leg which being of metal will be free from the objections to wooden legs and which in other respects structurally will be an improvement in regard to the matters of adjustment for wear and convenience of removing and replacing the box of the crank shaft by which the swinging or oscillating movement is imparted to the legs. To this end, my invention consists in the leg having 25 the characteristics of construction substantially as hereinafter specified and claimed.

In the accompanying drawings,

Figure 1 is a perspective view of a leg and enough of a tubing machine to illustrate my invention;

Fig. 2 is a detail view in perspective of the leg shown removed from the machine.

Fig. 3 is a detail view partly in section and partly in side elevation of the adjusting 40 device.

The leg 10 is a one-piece or integral cast-iron member having at its top the half box 11 by which it is pivotally hung and at its bottom the triangular shaped extremity 12 45 for the attachment and support of the usual foot.

The crank shaft 13 at each end as usual engages a box 14 that is slidably connected with the leg in order to allow the turning 50 of the crank to swing or oscillate the leg. The crank box is guided in its rectilinear movement by a pair of wedge bars 15 which engage the box on opposite sides and their box engaging faces being parallel, the in- 55 clination being on the outer face of each

wedge and the inclined outer face of each wedge engages the correspondingly inclined side surface of a slot 16 which extends longitudinally of the leg. Each wedge is adjustably secured in place by the bolts 17 so for each of which a slot 18 is provided in the leg so that by the longitudinal adjustment of the two wedges their inner box engaging sides may be nicely adjusted to take up or compensate for wear. The crank box 60 can be removed when necessary merely by the removing of the wedges and without any disturbance of the crank shaft.

For each of the bolts 17 there are two tapped holes 19 in the wedge in one or the other of which the bolt is placed. As the bolt can thus be shifted to different positions longitudinally of the wedge, I am enabled to make the slot 18 shorter which is an important consideration in that it avoids weakening the leg.

Extending between the two wedges at their upper ends is a steel bar 20 which has each end reduced and formed into a round horizontal projection 21 that enters a hole 80 in the contiguous wedge and slidably fits therein so that in the up and down motions of the wedges, they may move thereon toward and from each other. At its center, said bar has a tapped hole which is engaged by 85 the threaded portion of a vertical bolt 22 which passes through a bridge or cross bar 23 on the leg with its head above the bridge while below the bridge it is provided with a lock nut 24. Said cross bar with the bolt 90 forms a safety device so that should the screws 17 become loose the wedges will nevertheless not drop and it also is a means for the vertical adjustment of the wedges.

The wooden leg ordinarily used is built up 95 of several pieces which are secured together by bolts, and is a construction undesirable from the manufacturing standpoint and also because the warping of the wood impairs the alignment of the machine parts and renders 100 it worthless. By my invention since the leg is in one-piece and is of metal, preferably cast iron, the objections to the wood construction are obviated and the wedge adjustment device becomes entirely practical.

Having thus described my invention what I claim is:

An oscillating member having a journal box at one end and a foot attaching enlargement at the other end and a slot with oppo- 110

ned sides, in combination with a box situated in said slot, wedges the sides of the box in the slot, a tending between and slidably con- h the wedges, and an adjustable r said cross bar.

is patent may be obtained for five cents each, by addressing the "Commissioner of Patents, Washington, D. C."

In testimony whereof I affix my signature in presence of two witnesses.

FRED BLATTNER, JR.
